(57) **CLAIM**

The ornamental design for a wallet as shown and described.

DESCRIPTION

FIG. 1 is a top plan view of a wallet embodying my new design;

FIG. 2 is a right-side elevational view thereof;

FIG. 3 is a front elevational view thereof;

FIG. 4 is a bottom plan view thereof;

FIG. 5 is a left-side elevational view thereof;

FIG. 6 is a rear elevational view thereof;

FIG. 7 is a first perspective view taken from above showing the top, front and right side thereof;

FIG. 8 is a second perspective view taken from above showing the top, rear and right side thereof;

FIG. 9 is a third perspective view taken from below showing the bottom, front and left side thereof; and,

FIG. 10 is a fourth perspective view taken from below showing the bottom, rear and left side thereof.

The broken lines show portions of the wallet that form no part of the claimed design.

1 Claim, 4 Drawing Sheets
